(57) **CLAIM**

The ornamental design for a oval sidemarker lamp, as shown and described.

DESCRIPTION

FIG. 1 is a perspective plan view of a first embodiment of our new oval sidemarker lamp design.

FIG. 2 is a top plan view of a first embodiment of our new oval sidemarker lamp design.

FIG. 3 is a first side elevational view of a first embodiment of our new oval sidemarker lamp design.

FIG. 4 is a second side elevational view of a first embodiment of our new oval sidemarker lamp design.

FIG. 5 is a bottom plan view of a first embodiment of our new oval sidemarker lamp design.

FIG. 6 is a first end elevational view of a first embodiment of our new oval sidemarker lamp design.

FIG. 7 is a second end elevational view of a second embodiment of our new oval sidemarker lamp design.

FIG. 8 is a perspective plan view of a second embodiment of our new oval sidemarker lamp design.

FIG. 9 is a top plan view of a second embodiment of our new oval sidemarker lamp design.

FIG. 10 is a first side elevational view of a second embodiment of our new oval sidemarker lamp design.

FIG. 11 is a second side elevational view of a second embodiment of our new oval sidemarker lamp design.

FIG. 12 is a bottom plan view of a second embodiment of our new oval sidemarker lamp design.

FIG. 13 is a first end elevational view of a second embodiment of our new oval sidemarker lamp design; and,

FIG. 14 is a second end elevational view of a second embodiment of our new oval sidemarker lamp design.
